UNITED STATES PATENT OFFICE.

ROBERT DAWES, OF PHILADELPHIA, PENNSYLVANIA, ASSIGNOR OF TWO-THIRDS TO EDMUND DAWES, OF SAME PLACE, AND EDWARD H. HAS-KELL, OF BOSTON, MASSACHUSETTS.

TWISTING AND WINDING MACHINE.

SPECIFICATION forming part of Letters Patent No. 590,828, dated September 28, 1897.

Application filed December 26, 1896. Serial No. 617,041. (No model.)

To all whom it may concern:

Be it known that I, ROBERT DAWES, a citizen of the United States, residing in Philadelphia, Pennsylvania, have invented certain 5 Improvements in Spinning or Twisting and Winding Machines, of which the following is a specification.

My invention consists of certain improvements in the spinning or twisting and winding machine for which I have obtained Letters Patent No. 481,787, dated August 30, 1892, and No. 552,217, dated February 4, 1896, one of the objects of my present invention being to provide simple and efficient means 15 for guiding and retaining the rope or cord in its course from the draft-capstans to the spool upon which it is being wound, and a further object being to prevent the access of fine dirt, lint, or other foreign matters to the bearing 20 of the ring in the annular traverse-frame. These objects I attain in the manner herein-after set forth, reference being had to the accompanying drawings, in which—

Figure 1 is a view of sufficient of a spinning 25 or twisting machine to illustrate my present invention. Fig. 2 is an end view of part of the machine. Fig. 3 is a sectional view of part of the mechanism shown in Fig. 1, but with some of the devices in a different position from that illustrated in said Fig. 1. Fig. 4 is a transverse section on the line $x-x$, Fig. 1; and Figs. 5 to 9, inclusive, are detached views of parts of the machine, Figs. 5 to 8, inclusive, being on an enlarged scale.

So far as the general construction and operation of the spinning and winding machine is concerned it is similar to that set forth in my former patents, and hence need not be specifically set forth herein further than to 35 say that 1 represents the flier-spindle; 2, the longitudinal bars of the flier; 3, the spindle which supports the spool upon which the rope or cord is to be wound, and 4 the annular traverse-frame which surrounds the flier and 45 is moved to and fro throughout the length of the spool by suitable mechanism. This annular traverse-frame is grooved or recessed for the reception of a ring 5, having projecting ears 6, to which are bolted corresponding ears 50 upon segmental shoes 7 and 8, (see Figs. 5

and 6,) these shoes embracing the longitudinal bars 2 of the flier and being free to move longitudinally thereon.

Secured to each of the longitudinal bars of the flier, near one end of the same and in line 55 with the draft-capstans 9, is a split ring 10, which is clamped upon the longitudinal bar of the flier by means of a transverse bolt 11, said ring having a guide-block 12, with inner curved or rounded face, as shown in Fig. 1. 60 A similar curved or rounded lip 13 is formed upon the inner shoe 8, as also shown in Fig. 1, and the rope or cord after leaving the draft-capstan 9 passes up around the curved block 12, and thence through a recess in the inner 65 side of the bar 2 of the flier to the shoe 8 and down over the curved lip 13 of the same to the spool, the recess in the rod 2 of the flier extending almost from end to end of the same, so as to provide for the necessary longitudinal 70 traverse of the shoe 8 in laying the rope or cord upon the spool. By this means the rope or cord is guided in its course from the draft-capstan to the spool without the use of any sheaves or other like moving parts subject to wear and requiring lubrication, the 75 grooves or recesses in the inner side of the rod 2 of the flier-frame serving to prevent the rope or cord from being thrown outward by centrifugal force beyond the limits of said 80 frame, thus preventing the breaking of the rope or cord, which sometimes results when it is not thus confined. It will be noted that the shoe 8 does not project into the groove or 85 recess of the bar 2. Hence there is no frictional retardation of the longitudinal movement of the shoe which is likely to attend the movement of any guiding device which does project into said groove, owing to the accumulation of lint or other foreign matters in the 90 groove in such quantity as to bear upon the sides of such projecting guide.

The spindle 3, which supports the spool, has near its outer end a groove 14, and when the spindle is fully inserted this groove receives 95 the notched lower end of a sliding plate 15, mounted on a bracket 16 at the end of the machine and capable of being secured in position by means of a thumb-nut 17, which is adapted to a threaded stud or bolt projecting 100

outwardly from the bracket 16 through a slot in the plate 15.

The driving-belt of the machine can be shifted from the fast pulley 18 of the same 5 onto the loose pulley 19 by the movement of a shifter-bar 20, and it is thus shifted when a spool has been wound and is to be removed from the machine, the spindle 3 being first withdrawn longitudinally to such an extent 10 as to permit the spool to be removed from the flier.

In order to prevent the accidental starting of the machine when a spool and the spindle have thus been removed, I connect to the 15 sliding plate 15 a lever 21, which is connected by a rod 22 to a catch-arm 23, suitably hung to the lower end of the machine and having a lug 24 for engagement with any available 20 projecting part of the belt-shifting bar 20 when the latter is projected, so as to direct the belt onto the loose pulley 19, such engagement of the catch-arm 23 and belt-shifting bar 20 being effected by lifting the lever 21 in order to raise the plate 15 and free the spindle 3. 25 The machine cannot be again started, therefore, until the plate 15 and lever 21 have been again intentionally depressed, and this movement will not take place until a fresh spool has been supplied to the flier and the spindle 30 3 has been again inserted to the point at which it can be locked by the depression of the plate 15, such movement withdrawing the lug of the catch-arm 23 from engagement with the belt-shifting bar 20, so as to permit the movement 35 of the belt from the loose pulley onto the fast pulley.

Although I prefer the use of the lever 21 as a means of simultaneously operating the plate 15 and catch-arm 23, said catch-arm 40 40 may be connected to the plate in any available manner, so as to insure simultaneous operation of the two.

In order to render unnecessary the lubrication of the bearing of the ring 5 in the 45 45 traverse-frame 4, I line with graphite each side of the recess formed in said frame for the reception of the ring, the graphite being preferably in the form of plugs 25, filling openings formed in annular washers 26, which 50 are suitably secured to the frame 4—as, for instance, by screws 27, Fig. 8.

The washers 26 are preferably made in sections, as shown in Fig. 9, for convenience of handling, application, and removal.

In order to prevent the access of fine dirt, 55 lint, or other foreign matters to the bearing of the ring 5 in the frame 4, I provide said ring with flanges 28, projecting laterally from each side of the same close to the inner face of the frame 4, so that foreign matters thrown 60 outward by centrifugal force will strike these flanges and will thus be prevented from gaining access to the bearing.

Having thus described my invention, I wish it to be understood that I do not claim, 65 broadly, the recessed bar of the flier-frame, as such recessed bars have hitherto been employed, but I claim as my invention and desire to secure by Letters Patent—

1. The combination in a winding-machine, 70 of a spool-holder, the flier having a bar with recess in its inner side, and a shoe sliding along the inner side of said bar, and having a curved lip for directing the rope or cord from the recessed bar of the flier onto the spool, 75 substantially as specified.

2. The combination in a winding-machine, 80 of a spool-holder, a flier having a bar with recess on its inner side, a traverse-frame having a shoe with curved lip for directing the 85 rope or cord toward the spool, and a bearing-block for receiving the cord or rope from the draft-capstan and directing it through the grooved bar to the shoe, substantially as specified.

3. The combination of the spool-holder, the traverse-frame, the ring adapted to a groove or recess therein, the longitudinal bar of the flier recessed on the inner side, a shoe secured to the traverse-ring and engaging said bar, 90 90 said shoe having a curved or rounded lip, and a block secured to the flier-bar and serving to direct the rope or cord to the shoe on the traverse-ring, substantially as specified.

4. The combination of the recessed annular 95 traverse-frame, the flier-frame, and the ring rotating therewith and adapted to the recess of the annular traverse-frame, said ring having lateral flanges extending completely around the same close to the inner face of the annular 100 traverse-frame, substantially as specified.

In testimony whereof I have signed my name to this specification in the presence of two subscribing witnesses.

ROBERT DAWES.
